UNITED STATES PATENT OFFICE.

GEORGE HENRY WALKER, OF WORCESTER, ENGLAND, ASSIGNOR TO HEENAN & FROUDE, LIMITED, OF MANCHESTER AND WORCESTER, ENGLAND.

DYNAMOMETER.

Application filed March 28, 1921. Serial No. 456,088.

To all whom it may concern:

Be it known that I, GEORGE HENRY WALKER, a British subject, residing at Worcester, county of Worcester, England, 5 have invented certain new and useful Improvements in Dynamometers, of which the following is a specification.

This invention relates to improvements in rotary absorption dynamometers of the well 10 known "Froude" type.

In the specification of Harrison's prior U. S. Patent No. 1,035,700, there have been described means for regulating the output of the dynamometer by means of automatically controlling the admission and discharge of water to and from the dynamometer casing, in such a way that the output is proportionate to the quantity of weights which are suspended at the end of the balance arm. With such an arrangement the closing of the output valve chokes water back into the dynamometer casing, and has the effect of increasing the power absorbed by the dynamometer with the consequence 25 that the dynamometer casing tends to rotate on its trunnions, and to overcome the dead load of weights which are suspended at the end of the lever arm. Immediately the arm starts to rise above the horizontal, the rotation of the casing carries the outlet valve body with it, and the outlet valve is set to open when this occurs. The water passing out from the dynamometer casing then has an easier means of egress; the casing is partially emptied of water, and the amount of power absorbed by the dynamometer falls, with the result that the dead weights suspended at the end of the lever arm are immediately capable of depressing the arm, 35 closing the outlet valve until finally the power absorbed by the brake is sufficient to cause the lever arm to float, while suspending the dead load of weights suspended at the end of it.

40 It will thus be evident that in order to vary the power absorbed by the dynamometer, it is necessary to add to, or reduce, the number of weights suspended at the end of the lever arm. When the dynamometer is in action absorbing power developed by any prime mover and the lever arm floating approximately horizontally, the act of adding a weight to the dead load already in place at the end of the arm has the natural effect 45 of depressing the arm, and causing the out-

let valve partially to close, as just explained. This causes the dynamometer to start absorbing more power until the additional weight has been balanced; the arm then continues to float in a new position which 60 is slightly lower than the first. Similarly reduction in weight at the end of the arm will cause the outlet valve to open slightly, allowing the water to flow more freely out of the dynamometer casing, and diminishing the power absorbed by the brake until again it equals the torque represented by the weights suspended at the end of the lever arm. Hitherto it has not been found possible to apply this system of control to reversible dynamometers fitted with two rotors, one for absorbing power ahead and one astern, owing to the fact that in changing the direction of rotation of the dynamometer, the ordinary outlet valve gear would 75 have caused the valve to open instead of shut, and vice versa.

The present invention has for its object to arrange a system of valves and valve operating gear such that the output of the 80 dynamometer, irrespective of the direction of rotation, is automatically proportioned to the amount of load, represented by weights acting upon an extension or arm of the dynamometer casing.

85 The invention will be fully described with reference to the accompanying drawings.

Fig. 1. is an end elevation of two armed dynamometer with the brake bands of the 90 valve operating gear in section.

Fig. 2. is a front elevation of two armed dynamometer.

Fig. 3. is a vertical section to an enlarged 95 scale through controlling valve.

Fig. 4. is a longitudinal section of same.

Fig. 5. is a view to an enlarged scale of stop mechanism of the valve operating gear.

Fig. 6. is a diagrammatic view of the 100 weighting arrangement of a one armed reversing dynamometer.

The compartment of the dynamometer casing C which with its rotor absorbs power in a clockwise direction of rotation, is separated from the compartment which absorbs 105 power, in a counter-clockwise direction, by means of a partition between the two compartments which prevents water from circulating from one compartment to the other.

The main inlet water pipe A is split up 110

- into two branches a , a' , in each of which is inserted a valve B or B' respectively by means of which the water may be allowed to flow, or may be prevented from flowing 5 into the dynamometer casing, one valve B controls the flow of water into the one compartment, and the other valve B' controls the flow of water into the other compartment of the dynamometer casing.
- 10 The main outlet pipe D is also connected to two branch outlet pipes d and d' connected respectively to the outlets from the two compartments of the casing and in each of the pipes d and d' is inserted a valve E E' 15 by which the egress of the water from the compartments can be governed. The valve E controls the water passing out of one compartment and the valve E' the water passing out of the other compartment.
- 20 The valves B B' E E' are of the same construction as shown in Figs. 3 and 4. Each valve consists of a body F fixed to the dynamometer casing C so that when the casing rocks on its trunnions C' it carries 25 the body of the valve with it in the same direction. The central plug F' of the valve is connected by a series of levers and links with knuckle joints (which will be described later) to an immovable part of the dynamometer casing so that when the valve body F is moved the plug F' is caused to rotate through part of a circle and thereby alter 30 the position of the ports f' in the plug relative to the ports f^2 in the cylindrical sleeve F^2 carried in the body F thus altering the effective area of the valve opening.
- 35 Moreover the water entering the valve under pressure presses equally on diametrically opposite positions of the plug F' , so that the water pressure has no tendency to force the plug F' so closely into engagement with the body F as to cause difficulty in turning it.
- The dynamometer casing is provided with 40 two lever arms G and G' the arm G counterbalancing the resistance of the dynamometer when running clockwise and the arm G' counterbalancing the resistance when running anti-clockwise.
- 45 At one end of the shaft C^2 of the rotor is fixed an operating gear K for controlling the outlet valves E E' . The operating gear K consists of a brake band k encircling the dynamometer shaft C^2 , the necessary grip 50 being obtained by means of springs k^2 tending to close the two halves of the brake band k so that the rotation of the shaft C^2 tends to carry the brake band k with it, and to throw the links of the valve gear in 55 a certain direction. This action continues until the brake band k has reached a certain position, when a projecting lever k^2 hits against a stop k^3 or a stop k^4 fixed to a stationary part of the dynamometer supports 60 or casing. The lever k^2 in turn operates a

cam k^5 which separates the two halves of the brake band against the action of the springs, and removes the pressure of the brake band upon the shaft. This is a mechanical detail which avoids excessive pressure, and consequently heat, being developed by the rubbing surfaces of the brake when the dynamometer is running continuously.

The operating gear K is connected to the outlet valve E of the near compartment (looking in the direction of the arrow Fig. 2) by the link m , lever m' , shaft m^2 , screwed rod m^3 , lever m^4 , shaft m^5 , lever m^6 , rod m^7 and rod m^8 . The connections to the valve E' of the far compartment are the same to the rocking shaft m^5 which is connected through the lever m^9 , rod m^{10} and rod m^{11} to the valve E' . The setting of the two valves is such that when the direction of rotation is clockwise, the trip gear takes up a position (regulated by the position of the stop) such that the outlet valve of one rotor compartment is partially closed, causing power to be absorbed in this compartment of the casing. The other outlet valve being controlled by the same system of levers and links is thrown into approximately a fully open position permitting water to flow easily away from the casing, and allowing the rotor in this particular compartment to revolve idly.

The inlet valves B and B' are controlled by an operating gear N of similar construction to the operating gear K and operated in the same manner. The operating gear N is connected to the inlet valve B' of the far compartment (looking in the direction of the arrow Fig. 2), through the link n , link n' , shaft n^2 , lever n^3 rod n^4 and screwed rod n^5 . The inlet valve B of the near compartment is connected to the trip gear N through the link n , link n' , shaft n^2 , lever n^6 , rod n^7 and screwed rod n^8 .

The two inlet valves B B' are used only as distributors and not as regulators of the quantity of water supplied. They are always fully open, or fully closed, according to the position of the operating gear working under the influence of the rotation of the shaft, so that the rotor compartment in which power is being absorbed receives a full supply of water through the inlet valve which is open, while the idle compartment is starved of water.

When the direction of rotation of the dynamometer is counter-clockwise, the balance weights which control the amount of power absorbed are suspended upon the right hand lever arm G (Fig. 1). When the direction of rotation is clockwise, these weights are suspended on the left hand lever arm G' .

In dynamometers of large size, the number of balance weights which have to be sus-

pended at the end of the long arm in order to counterbalance the resistance of the dynamometer to rotation becomes unwieldy, and the weighing device shown in Fig. 14 may 5 then be adopted. At the end of the dynamometer arm G is mounted a vertical link g connected to a horizontal lever g' pivoted on a fixed fulcrum g^2 . At one end of the lever g' balance weights w or w' are suspended according to the direction of rotation of the 10 dynamometer. A sliding weight w^2 moving over a scale s is also provided on the lever g' .

What I claim as my invention and desire to protect by Letters Patent is:—

- 15 1. A rotary reversing absorption dynamometer of the type referred to comprising in combination a casing divided into compartments, a load arm extending therefrom, a rotor arranged in the casing, a shaft carrying the rotor, inlet and outlet pipes from the compartments, valves arranged in said pipes, operating gears mounted on the shaft carrying the rotor and links and levers connecting the operating gears to the valves.
- 20 25 2. A rotary reversing absorption dynamometer of the type referred to comprising in combination a casing divided into compartments, a rotor arranged in the casing, a shaft carrying the rotor, inlet and outlet pipes from the compartments, valves arranged in the outlet pipes, an operating gear mounted on the shaft carrying the rotor and

links and levers connecting the operating gear to the valves to operate the latter.

3. A rotary reversing absorption dynamometer of the type referred to comprising in combination a casing divided into compartments, a rotor arranged in the casing, a shaft carrying the rotor, inlet and outlet pipes from the compartments, valves arranged in the inlet pipes, an operating gear mounted on the shaft carrying the rotor and links and levers connecting the operating gear to the valves to operate the latter. 35 40

4. A rotary reversing absorption dynamometer of the type referred to comprising in combination a casing divided into compartments, a rotor arranged in the casing, a shaft carrying the rotor, inlet and outlet pipes from the compartments, valves arranged in said pipes, brake bands surrounding the shaft carrying the rotor, two springs controlling the brake bands, stops to limit the movements of the band and links and levers connecting the brake bands to the 50 55 valves to operate the latter.

In testimony whereof I have hereunto set my hand in presence of two subscribing witnesses this 11th day of March, 1921.

GEORGE HENRY WALKER.
